DESIGN FOR A COMBINATION BOTTLE AND
DISPLAY PACKAGEDon Eliot, Los Angeles, Calif., assignor to
Armand A. Dekama

Application September 20, 1937, Serial No. 71,697

Term of patent 7 years

To all whom it may concern:

Be it known that I, Don Eliot, a citizen of the United States, residing at Los Angeles, county of Los Angeles, State of California, have invented a new, original, and ornamental Design for a Combination Bottle and Display Package, of which the following is a specification, reference being had to the accompanying drawing forming a part thereof.

Figure 1 is a view in front elevation of a combination bottle and display package showing my new design. The opposite side of the article

shown in this figure has substantially the same appearance as the side illustrated.

Figure 2 is a top view of a combination bottle and display package showing my new design.

The dominant feature of the design resides in the portion shown in solid lines.

I claim:

The ornamental design for a combination bottle and display package, as shown and described.

DON ELIOT.
